OLIVER E. BUCKLEY, OF MAPLEWOOD, NEW JERSEY, ASSIGNOR TO WESTERN ELECTRIC COMPANY, INCORPORATED, OF NEW YORK, N. Y., A CORPORATION OF NEW YORK.

LONG SUBMARINE TELEGRAPH CABLE FOR OPERATION AT HIGH SPEED.

Application filed August 16, 1921. Serial No. 492,725.

This invention relates to the art of telegraphy, and particularly to an inductively loaded conductor for long submarine telegraph cables.

5 An object of this invention is to provide a loaded telegraph conductor over which signals may be transmitted at far greater speeds than have heretofore been possible.

Figs. 1 and 2 are diagrams that will be referred to in discussing the principles of the invention; Fig. 3 is a section of a furnace for annealing the loaded conductor; and Fig. 4 is a circuit diagram for a telegraph cable embodying the invention.

15 Long submarine telegraph cables have commonly been of one type, a single copper conductor surrounded by a layer of insulating material, usually gutta percha, and provided with a protective sheath. With a cable of this type, the maximum speed of transmission which may be attained is limited by certain factors, notably electrostatic capacity, resistance, transmitting voltage and interfering disturbances.

20 Some gain in speed might be secured by decreasing the resistance or capacity or both, but the factors of cost and mechanical difficulties have heretofore been considered to have set a practical limit of conductor diameter about .2 inch and diameter over gutta percha about .45 inch.

25 In common practice, it is considered desirable to limit the sending voltage to 50 volts; higher voltages involve some risk of breaking down the insulation, and this is considered the limit for safety. A long ocean cable, without any battery electromotive force applied thereto, may have frequent slight currents set up by practically 30 unknown electromotive forces. Similar currents are also encountered in land telegraphy, and somewhat similar in character is the so-called "static" which limits operations in radio telegraphy and telephony. In ordinary cases in the past it has been considered that in long submarine telegraph lines, the received current should be about 10 micro-amperes in order that it may be easily detected in comparison with the interfering disturbances that have been mentioned.

35 In the case of a relatively large cable of length 2000 nauts, suitable for transoceanic operation, having a conductor of 660 pounds

of copper per naut, and insulated with 400 55 pounds of gutta percha per naut, the frequency is limited by interference to about 10 cycles per second, and if about 10 micro-amperes is to be received on 50 volts sending, the frequency must be even less than 10. 60 Whatever the system of signaling employed there will be some limiting frequency of transmitted impulses necessary to be received discretely in order to make the signals intelligible, this being ordinarily designated 65 as the signaling frequency. If this speed of signaling is attempted to be increased above 10 cycles per second in the specific cable here mentioned, then the signals will be attenuated to such a degree that the normal 70 electrical disturbances will mask them and prevent their accurate interpretation.

75 It has long been known that, in general, the attenuation of signals by transmission lines could be reduced by the addition of inductance in proper amount. Many proposals have been made in the past to improve submarine telegraph cable operation by the use of added inductance. However, most of these proposals have had the primary object of reducing distortion rather than attenuation, since distortion has been the factor which, until recently, has practically limited the speed of signaling.

80 It will be understood that distortion in telegraphy results from an unequal attenuation of the sine wave components for various frequencies, and a relative phase shift among these components. Within recent years means have been developed for correcting distortion to any necessary degree, so that at present the correction of distortion no longer makes desirable loading of the line. The principal advantage to be gained by loading is reduction of attenuation 85 relative to the unloaded line for the frequencies involved in signaling, so that a higher signal speed can be employed without misinterpretation of the signals due to the normal disturbance currents.

90 Two ways of loading submarine cables have been used for relatively short telephone cables. These are coil loading by means of inductance coils at suitable intervals in series with the conductor, and continuous loading by means of a layer of iron wire wrapped directly around the conductor. In many cases, such telephone cables 95 100 105

have been used for superposed direct current telegraphy, but the loading has been of substantial advantage only for the telephone service and for high frequency carrier telegraph service. In practically no case has any mere telegraph cable been loaded, whether long or short, and the fact that telegraphing has been done on loaded cables is only incidental to the circumstance that they 10 were intended primarily for telephony and were loaded for that purpose.

The longest cable that has been loaded for telephone purposes to the present time has a length of about 110 miles. This cable is continuously loaded by means of a wrapping of iron wire. In a few instances, short telephone cables have been laid with elongated loading coils at intervals within the insulation, but mechanical difficulties present a 20 serious obstacle to this practice.

Aside from attempting to increase the speed of long lines by the addition of inductance, another proposal that has been considered is to introduce leaks at points 25 uniformly distributed along the lines. This corrects distortion to a certain extent, but greatly increases attenuation, so that it is not considered to be an advantageous expedient on the whole.

30 Notwithstanding the well-recognized desideratum of a suitable inductance loading for a long submarine telegraph conductor, and that no scheme for loading such a conductor, whether long or short, has ever been demonstrated to be advantageous, it has now 35 been found that a long telegraph cable can be continuously loaded in a practical manner with a composition of especial characteristics which will be pointed out, so that 40 it will transmit telegraph signals at speeds many times those which are possible with the ordinary non-loaded cable, or indeed with a cable continuously loaded in accordance with the plans hitherto proposed. 45 The important advantage of using this composition lies in the fact that although its permeability at higher magnetizing forces may be no greater than that of iron, nevertheless, at the low magnetizing forces encountered in a telegraph cable, its permeability is much higher than that of iron. For one-way sending in an ocean cable, the received current may fall as low as 10 micro- 50 amperes, or even lower, which corresponds to an exceedingly low magnetizing force. Even at the sending end, where the full effect of the 50 volt applied electromotive force is felt, the current will give a magnetizing force of only about 0.2 electromagnetic unit. Thus, the composition which is 55 contemplated for use has its remarkably high permeability within the range of magnetizing forces corresponding to those associated with signaling currents in a long submarine conductor.

It has already been mentioned in this specification that loading has never been found advantageous for telegraph conductors, although it has been found advantageous for telephone conductors. In order to analyze 70 the question of continuous loading in a precise manner, it will be desirable to establish a basis of comparison for loaded and non-loaded conductors. It might be supposed that the proper comparisons would be between a non-loaded conductor and a combination comprising that same conductor with the loading material wrapped around it. But the addition of the loading material necessitates more insulating material and 80 makes a more expensive cable, and it may be that if copper were added in place of the loading material, the received current would be even greater than for the loaded conductor. Thus it will be seen that a better basis 85 of comparison is that the conductor and the loading material combined shall have the same over-all diameter as the unloaded conductor. That is, the loading material should be considered as replacing an outer layer 90 of the copper conductor; if the loaded conductor does not offer advantage under this condition, it would be better not to replace the copper with loading material.

Accordingly, the question of setting up a 95 criterion for the advantage of loading presents itself as follows—What are the conditions that will make it advantageous to replace a vanishingly thin outer shell of the conductor by loading material? This leaves 100 the question of the optimum thickness of the loading material to be determined later, but at present we are seeking the condition as to whether the optimum thickness should be zero, or some amount not yet determined, 105 greater than zero.

The problem of telegraphic transmission of signals is fundamentally one of transients. However, in a case where the speed of signaling is limited by attenuation and interference, which is the case with which we are concerned, the question of maximum speed of signaling can be more conveniently discussed with reference to what happens to a steady alternating current. This results 115 from the fact that for any given system and speed of signaling there corresponds a frequency of transmitted impulses which must be received discretely in order to make the received signals legible. This frequency is ordinarily designated the signaling frequency. If a series of equal impulses alternately positive and negative are transmitted at this speed they are received approximately as a sine wave alternating current, the higher frequency components of the signals having been damped out by the cable. The attenuation of the series of impulses is thus approximately the same as the attenuation of a steady alternating current 120 125 130

of frequency in cycles per second equal to half the number of impulses per second, and if the signal is made up of an irregular combination of impulses the attenuation of the signal as a whole when properly corrected by terminal circuits, may be determined by the attenuation of a steady alternating current of frequency equal to half that of the highest frequency impulses necessary to be received in order to make the signal legible.

A formula will now be derived showing the relation that must be satisfied by the permeability and other factors so that the replacement of conductor material by loading material shall be advantageous.

The attenuation α per unit length for a current of frequency n in a continuously loaded conductor having per unit length the resistance R , capacity K and inductance L , is given by the well-known formula

$$\alpha = \sqrt{\pi n K} (\sqrt{R^2 + 4\pi^2 n^2 L^2} - 2\pi n L)$$

on the assumption that the leakance is negligible, which is an entirely valid assumption to be made in this case. Since we are considering the effect of a vanishingly thin outer layer of magnetic material, the value of L will be very small and the term

$$4\pi^2 n^2 L^2$$

will be so small in comparison with R^2 that it may be neglected, thus reducing the formula to

$$\alpha = \sqrt{\pi n K} (R - 2\pi n L)$$

Now, with a constant over-all radius r , we see that when we apply a layer of magnetic material of thickness t , we not only increase L but we diminish the cross-section of the conductor, and thereby increase R . Hence, to decrease α , we must increase the term $2\pi n L$ more than we increase the term R . Accordingly, taking the derivatives of these terms with respect to t , we must have

$$\frac{d}{dt} R < \frac{d}{dt} \cdot 2\pi n L$$

If the specific resistance of the conductor material is ρ , the resistance of the conductor per unit length is given by

$$R = \frac{\rho}{\pi(r-t)^2}$$

whence

$$\frac{d}{dt} R = \frac{2\rho}{\pi(r-t)^3}$$

Since we are dealing with a vanishingly thin layer of loading material, the foregoing equation reduces to

$$\frac{d}{dt} R = \frac{2\rho}{\pi r^3}$$

To obtain an expression for the inductance due to the layer of loading material,

we introduce first the well-known formula that

$$H = \frac{2I}{r}$$

70

which gives the intensity of the magnetizing force H at the surface of a conductor of radius r carrying current I . Assuming the permeability of the magnetic material is μ , the flux density B is given by the formula

75

$$B = \mu \frac{2I}{r}$$

and the flux per unit length of the conductor is

80

$$\phi = \frac{2I\mu t}{r}$$

But by the definition of inductance

85

$$L = \frac{d}{dI} \phi = \frac{2\mu t}{r}$$

whence

$$\frac{d}{dt} L = \frac{2\mu}{r}$$

89

Substituting in the critical inequality written out heretofore,

$$\frac{2\rho}{\pi r^3} < 2\pi n \cdot \frac{2\mu}{r}$$

93

or

$$\mu n > \frac{\rho}{2\pi^2 r^2}$$

100

Now,

$$\frac{\rho}{\pi r^2}$$

105

is the resistance R per unit length of the unloaded conductor, hence the inequality on which we rely as the criterion may be written

$$\mu n > \frac{R}{2\pi}$$

110

If the values of permeability μ , frequency n , and resistance R satisfy the foregoing inequality, then we are assured that the replacement of a vanishingly thin outer layer of conductive material by a similar layer of magnetic material will decrease the attenuation of a current therein, but if the three parameters mentioned do not satisfy this inequality, then it will be better to leave the conductive material in the space that would be occupied by the magnetic material. In other words, for a loading material to offer any advantage in the way of reducing attenuation, it is essential that the product of frequency by permeability shall be greater than a certain amount which is proportional to the resistance per unit length of the conductor.

115

Assuming that the resistance R is fixed, the foregoing inequality exhibits the fact

120

125

130

- that a magnetic material of a certain permeability may be highly advantageous in connection with telephone frequencies and of no advantage for telegraph frequencies.
- 5 Since the product μn must be larger than a certain amount, and since the frequency n is relatively high for telephony, the permeability μ need not be high, but when n is low as for telegraphy, then μ must be high to
- 10 make the product μn sufficiently large. This inequality also exhibits the fact that for given values of μ and n , a decrease of resistance R may change the situation from unfavorable to favorable for the addition of loading material.
- 15

Passing now to a specific example under this criterion, consideration will be given to a representative cable having a resistance of 1.80 ohms per naut, that being the resistance of the particular copper conductor of 660 pounds per naut heretofore mentioned. Changing to electromagnetic units, and performing the indicated division by 2π , the inequality reduces to

25

$$\mu n > 1540$$

The permeability to be considered in this connection is the initial permeability, that is, the permeability obtained at very low magnetizing forces. This is for the reason already pointed out, namely, that the magnetic field strength immediately outside the cable conductor is at the most only about 0.2 electromagnetic unit, and it decreases rapidly from that value at the sending end of the cable to a value of about 10^{-5} electromagnetic unit at the receiving end of the cable. At such low magnetizing forces, the permeability of the magnetic circuit when iron is employed as the loading material is only about 150. Hence we see that to satisfy the foregoing inequality, n must have a value of at least 10 cycles per second. If n , the signaling frequency, is less than 10 cycles per second, there will be no improvement in attenuation by adding continuous loading. On the other hand, although the criterion may apparently be satisfied by increasing n , the fact is that at higher frequencies the attenuation in a cable loaded with iron is so much greater that the signals will be unintelligible. The curve in Fig. 1, shows how abruptly the received current decreases with increasing frequency in an unloaded cable of fairly representative dimensions, but for somewhat ideal conditions.

In this figure, the ordinates represent the received current in micro-amperes for an impressed electromotive force of 50 volts, and the abscissæ represent the frequency in cycles per second.

Though it may sound paradoxical, loading with iron would be of advantage in such a cable for telephony, but the trouble would be that, at the high frequency employed, the

received current would be far too small to be appreciable and the boost that it would get on account of the loading would not be enough to overcome this difficulty.

It will be understood that for a case in which the criterion under consideration gives a barely favorable indication for loading, the optimum thickness of the loading material would be very small, less indeed than is practically necessary to apply the loading material, for it must be several thousandths of an inch thick. Accordingly, the inequality may be expressed with greater practical accuracy thus

$$\mu n > \frac{R}{2\pi} + \delta$$

where δ is an increment depending upon the circumstances, among which is the fact that we cannot deal in a practical manner with a layer of loading material of only vanishing thickness.

Another factor which would increase δ and which contributes to prevent the use of iron loading for even relatively short cables, is the circumstance that as soon as the loading material has a sensible thickness, it becomes the seat of eddy currents which increase the alternating current resistance of the cable as compared with its direct current resistance.

Still another factor which helps to prevent the use of iron loading even for relatively short cables is that of the difficulty of balancing for duplex operation. In order to operate a cable simultaneously in both directions, it is necessary to provide at each end a balancing network or artificial line having an impedance equal to that of the cable over the frequency range involved. To attain the speeds of present commercial practice over long cables, a very high degree of perfection of balance between the artificial line and the cable is required. A balance accurate to one part in ten thousand is often necessary with ordinary non-loaded cables, and the attainment of this degree of balance is a very difficult matter. However, the problem of balancing a continuously loaded cable is far more difficult than that of balancing a non-loaded cable, owing to the fact that the impedance is no longer constant even for a single frequency, but varies with the amplitude of the sending current as a result of the variation of the permeability of the loading material corresponding to variation of the magnetic field strength. Moreover, the problem of balance becomes increasingly difficult at higher speeds.

Of course this difficulty as to balancing a high speed loaded cable, say of 1,000 miles or over, may be obviated by operating in only one direction at a time, but in that case, for the continuously loaded cable to offer

advantage in traffic carrying capacity over the ordinary cable, it is necessary that the speed of the loaded cable be more than twice that of the one-way speed of the unloaded cable. Thus, in the case of the particular cable last specified, the normal one-way speed when unloaded was 10 cycles per second, but being operated duplex, its entire capacity was equivalent to one-way speed of 10 cycles per second. Now if iron were added as the loading material, this would inhibit efficient duplex operation and hence to compare favorably, the cable must have a one-way speed of 20 cycles per second when loaded. This is out of the question because, as previously stated, at the high frequency employed, the received current would be far too small to be appreciable.

In a tape-loaded cable the inductance per 20 naut is

$$L = \frac{7.42\mu t}{d-t} 10^{-4}$$

where d is the over-all diameter of the conductor and loading and t is the thickness of the tape. In this cable, with a copper conductor and with the loading material 78½% nickel and 21½% iron, the resistance per 30 naut (taking account of eddy current losses in the tape) is

$$R = \frac{6 \times 10^4}{(d-2t)^2} + \frac{2.2 \times 10^{-11} \mu^2 n^2 t^3}{d-t}$$

where d and t are expressed in thousandths 35 of an inch.

Substituting these values for L and R in the formula already given for attenuation α , gives the attenuation in the loaded cable.

In Fig. 2 are shown the results of computations which have been made by means of the foregoing formulas, giving the effect of permeability on signal speed in representative cases. The curves of Fig. 2 show the manner in which the maximum attainable frequency of signaling impulses varies with the permeability of loading material employed. Three cases are presented for which the conductor diameters in inches are respectively 0.150, 0.180, and 0.200. The capacities of the three cables are each assumed to be 0.4 microfarads per naut. In all of these cases, a length of 2,000 nauts is assumed. This length is fairly comparable with the length of the trans-atlantic cables 55 that connect Europe and North America, and, therefore, is convenient as an example for comparison. This invention is not applicable to short cables of the kind that connect England with the continent, Cuba with 60 the United States, etc., and 2,000 nauts is mentioned as a representative length, not as a limit.

For the curves of Fig. 2, a transmitting voltage of 50 volts is assumed, and it is also 65 assumed that the received current is about

10 micro-amperes. In computing these curves, the thickness of the loading material chosen was in each case the optimum thickness, that is, the thickness which would give the greatest received current; in other words, the thickness which would give the least attenuation. These thicknesses in thousandths of an inch are indicated by the numbers in parenthesis noted at corresponding points on the diagram. They vary from point to point along each curve. It will be noticed that for low values of permeability all the curves are substantially horizontal, indicating that the signaling speed is independent of the permeability. This is true because for low values of permeability, the optimum thickness of the loading material is zero, and since the signal speed is accordingly quite independent of the layer of loading material when its thickness is zero, the curves are horizontal straight lines in the range considered.

These curves take into account the eddy current losses in the magnetic material, calculated on the basis of a fixed resistivity but they do not take into account dielectric leakage or the resistance of the return path, which are quite negligible at low frequencies but may become appreciable at higher frequencies. The effect of including these losses would be to shorten the ordinates of the curves.

It will be noted that the smaller the diameter of the conductor, the larger becomes the required permeability to show any gain as a result of loading.

In order that the speed of the loaded cable may be twice that of the corresponding non-loaded cable, which, as has been pointed out, will be necessary if duplexing is abandoned, in order to make the loaded cable even barely worth while, there is required in the case of the conductor of 0.200 inch diameter a magnetic material of permeability about 310, and for the conductors of diameters 0.180 and 0.150 inches, respectively, the required permeabilities are seen to be about 600 and 1,350. Thus it is shown that iron, with a permeability of 150 or thereabouts, would be quite useless for loading cables of these dimensions, but that a material with a permeability several times that of iron would produce a very great increase in the permissible speed of signaling.

Silicon steel exhibits magnetic qualities superior to ordinary iron in some respects, but its employment is limited by its comparative brittleness and the difficulty of working it. The principal possible rivals of iron, namely, nickel and cobalt, are far below it in permeability at the magnetizing forces involved in telegraph signaling. With nickel and cobalt in this respect, stands Heusler's alloy of aluminum, manganese and copper. It has been found that a composi-

tion of two-thirds nickel and one-third copper, when tested at low magnetizing forces, gives a permeability higher than that of iron alone. It will be seen that with the exception of aluminum, all these metals stand close together in their atomic weights and atomic numbers, and in this specification the five elements, manganese, iron, nickel, cobalt and copper, having the consecutive atomic numbers, 25, 26, 27, 28, 29, will be referred to as belonging to the magnetic group of elements.

It has been found that by melting nickel and iron together in proper proportions, and by subjecting the composition to suitable heat treatment and mechanical treatment, a magnetic material is produced which has a very much greater permeability at low magnetizing forces than has iron. More particularly, by combining these two elements in proportion of 78½% nickel and 21½% iron, and subjecting them to appropriate heat treatment, and other treatment, a material is produced of extraordinarily high permeability at low magnetizing forces. When applied to a conductor in the form of a helical tape with the edges close together, it shows a virtual permeability of 2,000 or more. By reference to the curves of Fig. 2, it will be at once seen that for such high permeability, very great increases in speed are obtainable, whereas iron offers no advantage when used in the same way.

Although a permeability of 2,000 or more may be obtained by the use of the nickel-iron composition which is herein referred to as the loading material, it may not always be desirable to use material of the highest possible permeability, particularly in the case of cables of less length over which the signaling frequency may be relatively high and for which, accordingly, the alternating current losses are of considerable consequence. These losses result from causes among which are dielectric leakance, eddy currents in the loading material, hysteresis in the loading material, and resistance to the return current outside the cable core. Of these, only eddy current and hysteresis are primarily dependent upon the loading material. One of the properties of the nickel-iron composition, in addition to its high permeability at low magnetizing forces, is its remarkably low hysteresis, and this is one of its incidental advantages. One of the most important of the alternating current losses in the case of the continuously loaded ocean telegraph cable is that due to eddy currents. This factor increases in proportion to the conductivity and the square of the permeability of the loading material and to the square of the frequency. It is also dependent upon the dimensions of the tape. In order to reduce the eddy current losses for the loaded conductor, it may be desirable

to use a material of higher specific resistance than the nickel-iron composition which I have mentioned specifically, even though this higher resistance is obtained at the expense of lower permeability. Such a material of higher specific resistance may be obtained by adding chromium in moderate proportion to the nickel-iron composition already mentioned. It is also important to take into account the eddy current losses in determining the thickness of the loading material and to use such a thickness that the highest possible frequency will be received with the necessary current amplitude. It may be advantageous further to reduce the eddy current losses by applying the loading material in the proper thickness in the form of two or more layers separated by a film of oxide or other insulating material.

While 78½% and 21½% are mentioned as giving the proportion of the ingredients, nickel and iron, to be employed in making up the magnetic material, it will be understood that the proportion may deviate considerably from these figures when nickel and iron are the only ingredients, and that when there are other ingredients, this proportion may not apply. Up to the present time, when the only ingredients are nickel and iron, it has been found that a proportion about the same as has been named, gives the greatest permeability for low magnetizing forces. Other ingredients than nickel and iron may be employed for various purposes, not only to confer high permeability on the product but for other objects, such as to increase the specific resistance as shown by the example already mentioned of adding chromium, or to facilitate mechanical preparation of the loading material by making it more malleable. A composition of nickel 55%, iron 34% and chromium 11% has been carefully prepared, heat treated and tested, and found to give a permeability far higher than of iron and at the same time to give a resistivity higher than that of iron, and higher than that of the nickel-iron composition in the proportion of 78½% nickel and 21½% iron.

In constructing a loaded submarine telegraph conductor in accordance with the present invention, a copper conductor is provided having a relatively smooth exterior surface. The reason for having the conductor in this form is so that the position of the loading material relative to the conductor will suffer no change when the cable in which it is incorporated is submerged and thus subjected to rather large pressures in the depth of the ocean. As is well known, it is desirable to employ conductors made up of several strands so as to lend flexibility, thereby providing that a discontinuity of the electrical circuit will not be so likely to result from a break in the conduc-

tor as would be the case if only a single conductor were used. The conductor is, therefore, preferably made up of a central wire surrounded by a number of helically-wound flat copper tapes giving a smooth cylindrical exterior surface.

The particular dimensions of the loading material depend on factors peculiar to each particular case in which a loaded cable is to be used. For a conductor of 660 pounds per naut and of length 2,000 nauts, designed to operate at the maximum practicable speed, the nickel-iron loading composition should be approximately 0.006 inch thick and it may be conveniently applied in the form of a tape of that thickness and 0.125 inch wide wrapped in a closely laid helix about the conductor of diameter 0.178 inch.

The copending application of Elmen Serial No. 473,877, filed May 31, 1921, discloses and claims a magnetic material which has properties adapting it, among other purposes, to loading signaling conductors in accordance with this invention.

It will normally be found that the high permeabilities referred to in the foregoing part of this specification are not obtained merely by applying the loading composition in the manner described; to obtain the highest permeability and, consequently, the greatest inductance, it is necessary to give the loaded conductor an appropriate heat treatment. For this purpose the conductor specified is drawn lengthwise through the furnace of Fig. 3, which is maintained at a temperature of about 875° C. This is a muffle furnace, with the heating elements 1 between the fire clay muffle 2 and the fire brick 3. Around the fire brick 3 is a sheet iron outer wall. The iron tube 4 has a copper lining 5 of inside diameter a little over one-half inch. It extends clear across the furnace and projects 8 inches beyond the furnace walls at each end. The length of the pass through the furnace is about 2 feet and the rate of movement of the conductor therethrough is about $\frac{3}{4}$ foot per minute. As the taped conductor passes from the furnace and the projecting end of the tube 4-5, it cools in the air, which outside the tube 4-5 is at about normal room temperature, that is about 20° C. Under the conditions and for the dimensions as described, this gives a proper rate of cooling after heating in the furnace. The conductor should be led away straight from the furnace, far enough for it to become cooled; bending at this stage may impair its high permeability. Also the necessary cooling thereafter should be on a large radius, not less than 2 feet; the strains and stresses involved in coiling and uncoiling on a smaller radius may reduce the permeability.

While a certain speed and temperature

with a certain type of furnace have been described to produce the desired results in the case of a particular cable, it is apparent that these factors may be varied or adjusted to meet different cases, such, for example, as a cable of different diameter from that here discussed. In some cases it may be desirable to repeat this heat treatment several times in order that the strains in the composition may be completely removed and that the utmost high permeability desired may be established therein. Such a repetition of the heat treatment process may be particularly necessary in case the conductor is solid instead of being stranded.

Having prepared the bare loaded conductor, an insulating material such as Chatterton's compound is applied in such a manner that all of the interstices of the conductor and the strand are completely filled with this compound and a layer thereof adheres to the outside of the tape and serves to give good adhesion with the gutta percha insulation, which is applied next. The filling compound should be one which flows under a pressure even when cold. A relatively soft grade of Chatterton's compound has been found suitable for this purpose. The object of filling all the interstices of the conductor with Chatterton's compound is to provide assurance that when the cable is submerged the pressure applied to the loading tape will not tend to deform it, as might be the case if there were slight voids within the outline of the conductor. Thus it is assured that the great pressure to which the cable is subjected at ocean depths will merely subject the loading tape to a uniformly distributed pressure without distorting it. This is desirable because it has been found that the tape of magnetic material has its permeability seriously reduced if it is deformed.

The gutta percha insulation is applied to the loaded conductor in the manner ordinarily employed when insulating submarine cables.

As is the ordinary practice, a long ocean cable must be made up in a number of sections which will be joined together. If these sections differ in their characteristic impedance, it will be desirable to join them in such a way that these characteristic impedances are graded consecutively from one section to the next. If it is deemed desirable to have the characteristic impedances approximately the same at the two ends of the cable, this may be accomplished consistently with the foregoing requirements by dividing the cable sections into two groups, each arranged in the order of their impedances and connected so that the impedances increase gradually from each end to the approximate middle of the cable. Although uniformity of impedance is desir-

able, particularly from the standpoint of balancing with the artificial line in case the cable is to be operated duplex, nevertheless small variations in impedance from section to section are not serious, for the reason that the wave lengths involved in telegraph operation are quite long relative to the length of cable sections ordinarily manufactured.

10 In order to secure full benefit of the loading of the type described, certain precautions are necessary in connection with operation. In particular, means should be provided for eliminating or compensating 15 distortion so far as possible. Although the heavily loaded cable is described by some authorities as being substantially distortionless above certain signaling speeds, it has been found that actually it gives distortion 20 at all signaling speeds owing to the alternating current losses in the loading material, and it has also been found that it may introduce new kinds of distortion which are not present in non-loaded cables. 25 The principal types of distortion to which a loaded cable of this type is subject, are that due to unequal attenuation and phase shift of the component frequencies of the signal and that due to introduction of harmonics as a result of the magnetic peculiarities of the loading material. Another type of distortion may be introduced by magnetic hysteresis in the loading material, but in the case of the magnetic material particularly referred to in this specification, it is believed that this kind of distortion will not be serious in view of the very low hysteresis exhibited thereby.

30 The distortion due to unequal attenuation and phase shift of the different frequency components of the signal is similar to that which is produced by the non-loaded cable but is less in degree. This distortion may be reduced by the use of a proper compensating network at the terminals of the cable, which will reduce the amplitude of the components of frequencies lower than a certain maximum desired frequency to their proper value relative to that of the maximum frequency, that is, it is provided that all frequencies below the maximum frequency are attenuated alike by the combination of the cable and the network. By proper design 45 of the terminal network the necessary restoration of proper phase relations may also be secured.

50 A suitable circuit system to complete the cable in accordance with the foregoing principles is illustrated in Fig. 4, where the cable 6 is continuously loaded in accordance 55 with the disclosure of this specification. It is connected to ground through the transmitting apparatus 7 and condenser 8. At the receiving end the cable is connected to ground through two parallel branches. One

of these comprises a large inductance 9 in series with an adjustable resistance 10. The other branch comprises the condenser 11 and adjustable resistance 12 in multiple, this combination having series relation to the inductance coil 13 and adjustable resistance 14 in series with each other. The elements 8, 9, 10, 11, 12, 13 and 14 are comprised in the distortion-correcting apparatus. The inductance 13 and resistance 14 are shunted 70 by a potentiometer resistance 15, the taps from which complete the input grid circuit of the vacuum tube amplifier 16, whose output circuit comprises the recording instrument 17. This recording instrument 17 may 75 conveniently be a string oscillograph recording photographically on sensitized paper. The siphon recorder which is commonly used for non-loaded cables is too slow in operation for the high speed signals sent over the 80 improved loaded cable of this invention.

85 In place of the transmitting and recording apparatus which are shown, it may be advantageous to use the terminal apparatus of the well-known multiplex printing telegraph system in combination with a vibrating relay of the Gulstad type or of the synchronous type.

90 In certain cases advantage may be secured by using the carrier current system, 95 in which sinusoidal currents of definite moderate frequency are modulated by superposed signal impulses of lower frequency. Although the carrier current telegraph system has shown no advantage over the standard system for non-loaded cables, it may offer advantage in the case of continuously 100 loaded cables for the reason that the attenuation does not increase so rapidly with the frequency in the case of the loaded cable as 105 in the case of the non-loaded cable.

110 What is claimed is:

1. A long submarine cable conductor for signals of high telegraphic frequency loaded with a layer of nickel-iron composition of substantially higher permeability than iron at low magnetizing forces.

115 2. A long submarine cable conductor for signals of high telegraphic frequency continuously loaded with a composition comprising at least two magnetic elements, one of which is nickel, and in which the nickel component is within a few percent of 78½% of the magnetic element content.

120 3. A long submarine telegraph cable conductor enveloped by magnetic material comprising nickel and iron and having a permeability at least several times that of iron at magnetizing forces of two-tenths gauss or less.

125 4. A long submarine telegraph cable comprising a uniform conductor and uniformly distributed magnetic material of initial permeability so high that when multiplied by 2π times a frequency in the range of tele-

graphic frequencies transmitted, the product exceeds the conductor resistance, all magnitudes being measured in electromagnetic units.

- 5 5. A long submarine cable comprising a uniform conductor and uniformly distributed magnetic material comprising nickel and iron and having a permeability at magnetizing forces of .2 gauss or less such that when
10 the permeability is multiplied by 2π times a frequency within the range of frequencies transmitted, the product exceeds the conductor resistance, all magnitudes being measured in electromagnetic units.
- 15 6. A long submarine cable wrapped with spirally laid tape of a thickness not exceeding a few mils, and composed of an alloy comprising nickel and iron, the nickel content constituting more than half the total
20 weight of the alloy.

7. A long submarine cable wrapped with spirally laid tape of a thickness not exceeding a few mils composed of an alloy of nickel and iron and a substance to increase
25 the specific resistance thereof, and having a permeability greater than iron at magnetizing forces of .2 gauss or less.

8. A long submarine cable conductor for signals of high telegraphic frequency loaded
30 with a layer of magnetic material comprising nickel and iron, the nickel content being within a few per cent of 78½% of the nickel-iron content.

- 35 9. A long submarine telegraph conductor continuously loaded with magnetic material comprising at least two elements of the magnetic group, and means for telegraphing over said conductor at speeds exceeding 20 cycles per second.

- 40 10. A long submarine telegraph conductor continuously loaded with magnetic material comprising at least nickel and iron of the magnetic group, and means for telegraphing over said conductor at speeds exceeding 20
45 cycles per second, said material having a

permeability at least several times that of iron at the magnetizing forces involved.

11. A long submarine telegraph conductor loaded with a layer of magnetic material comprising at least two elements of the magnetic group, said material having so high an initial permeability, such high specific resistance, such low hysteresis effect and such dimensions that the attenuation of telegraphic signals is less than in a non-loaded conductor of the same dimensions as the combined conductor and said layer.

12. A submarine telegraph conductor continuously loaded with magnetic material comprising at least two elements of the magnetic group, said material having such high permeability, specific resistance, low hysteresis effect, and dimensions that the attenuation suffered by telegraphic signals transmitted at a speed between 20 cycles per
60 second and several times that rate is less than would be suffered by telegraphic signals of one-half that speed over a non-loaded conductor of the same outside diameter.

13. A long submarine telegraph conductor loaded with a layer of magnetic material comprising at least nickel and iron of the magnetic group and having a permeability at least several times that of iron at the magnetizing forces involved, and means for impressing telegraphic signals on said conductor at high speed, the attenuation of said signals in said conductor being less than for an unloaded conductor of the same dimensions as the combined conductor and said
75 layer.

14. A long submarine cable continuously loaded with a composition comprising nickel and iron, the nickel content constituting more than half the total weight of the alloy.

In witness whereof, I hereunto subscribe my name this 10th day of August A. D., 1921.

OLIVER E. BUCKLEY.
